UNITED STATES PATENT OFFICE.

DAVID BUMGARDNER, OF MERIDIAN, MISSISSIPPI.

FEATHER-CLEANER.

SPECIFICATION forming part of Letters Patent No. 224,384, dated February 10, 1880.

Application filed December 6, 1879.

To all whom it may concern:

Be it known that I, DAVID BUMGARDNER, of Meridian, in the county of Lauderdale and State of Mississippi, have invented a new and valuable Improvement in Feather and Hair Cleaners; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal sectional view of the drier, and Fig. 2 is a plan view of the cleaner complete.

This invention has for its object the improvement of machines for renovating feathers, hair, and other similar substances; and the nature of the invention consists in certain novel combinations of the devices used, whereby the substances to be renovated are cleaned and renovated without the direct contact of steam, as will be hereinafter more fully set forth.

In the annexed drawings, the letter A designates a boiler or steam-generator of suitable construction, and provided with the usual safety-valves and gage-cocks, if desired. B indicates a washer, consisting of a close box, a, having within it a rotary dasher, b, actuated by a suitable crank, c.

Leading from the steam-space of the boiler is a steam-pipe, C, provided with a regulating-cock, a', through which steam is let into box a, for the purpose of raising the temperature of the water to lukewarm heat, when impurities will be readily softened and removed without depriving the feathers of their natural oil, to which they owe their preservation and flexibility. Previous to washing steam is cut off from the box.

C' indicates the drying device, composed, essentially, of two steam-tight cylinders, D D', the one within the other, and having between them a steam-space, b', completely surrounding the cylinder D, whereof the interior is the drying-chamber.

Leading into the steam-space b' from the boiler is a pipe, c'', having a cut-off cock or valve, c'', by means of which steam is admitted to the space b', or shut off therefrom, and

its supply is regulated at pleasure. The water of condensation is drawn off from space b' at proper intervals through a cock, d, in the end of cylinder D'.

G indicates a tube extending through the ends of the cylinders D D', and fixed permanently and with a tight joint thereto. This tube connects with the boiler by means of a pipe, d', having a regulating cock or valve, d''.

As shown at e, Fig. 1, the other end of pipe G is rabbeted and extends completely through a short section of pipe H, having its bearings in the ends of the cylinders D D', and forming a steam-tight joint therewith. This pipe H is rotated by means of a pulley, H', on its outer end, and has rigidly secured to it, within the cylinder D', one of the heads, e', of an agitating-wheel, J, the other head, f, of which turns loosely on the tube G, and consequently the rotation of pipe H operates the wheel J to stir up the feathers in the cylinder D, which are introduced into it through a hinged door, closing an aperture in both cylinders. Steam is admitted into the pipe G through the steam-pipe d', and the water of condensation is let out therefrom by means of a cock, g, in its end.

It will be observed that the inner cylinder is not only surrounded by a steam-chamber, but that there is also a central chamber formed by pipes G and H, which, in connection with the exterior chamber, keeps up an equable temperature in all parts of chamber D.

It also will be seen that the feathers are dried without the direct contact of the steam therewith, whereby the volatilization of the oleaginous matters essential to their life and flexibility is prevented, and the dried feathers are preserved in a proper condition of springiness.

The peculiar arrangement of the pipe G, extending completely through the rotary pipe H, obviates the necessity of packing, which in small mechanisms is an exceedingly difficult operation.

What I claim as new, and desire to secure by Letters Patent, is—

1. The combination of a steam-generator, A, and the drier consisting of the cylinders D D', the one within the other, and having the steam-space b' between them, the pipe c'', leading from the boiler to the said space, the rotary

pipe H in one end of said cylinders, the pipe G fixed in the other end thereof, and having the rabbeted end e, extending through pipe H, the agitating-wheel J, fixed upon pipe H and 5 turning loosely on pipe G, and the steam-pipe d', leading into the pipe G, substantially as specified.

2. The steam-drier consisting of the cylinders D D', arranged the one within the other, 10 and separated by the steam-space b', the rotary pipe H, the pipe G, fixed in the cylinder ends and extending through pipe H, the agitating-

wheel J, fixed on the said pipe and turning loosely on the pipe G, and steam-pipes opening into space b' and into pipe G, substantially as set forth.

In testimony that I claim the above I have hereunto subscribed my name in the presence of two witnesses.

DAVID BUMGARDNER.
